PUSHER

Stoddard B. Martin, Cleveland, Ohio; Central National Bank of Cleveland, executor of said Stoddard B. Martin, deceased, assignor to Margaret J. Martin

Application August 26, 1944, Serial No. 551,317

7 Claims. (Cl. 279—46)

1

This invention relates to pushers for automatic screw machines and the like.

The principal object of this invention is to improve and simplify the installation and removal of work engaging pads in a pusher having a stronger stock gripping force on the forward, or stock advancing, stroke than on the retracting stroke. Other objects are to simplify and improve the arrangement and cooperation of a pusher and stock gripping pads by which the gripping force is increased on the advancing stroke and decreased on the retracting stroke. Other objects will appear in the following detailed description of preferred embodiments of the invention.

In the accompanying drawings:

Fig. 1 is a side elevation of a pusher, constructed in accordance with this invention, gripping a piece of stock;

Fig. 2 is a longitudinal section through the pusher on the line 2—2 of Fig. 1;

Fig. 3 is a cross section taken on the line 3—3 of Fig. 2;

Fig. 4 is a side elevation taken from the position indicated by the line 4—4 of Fig. 3 looking in the direction of the arrows; and

Fig. 5 is a longitudinal section through the pusher showing a different form of stock engaging pad.

Referring to the drawings, the pusher illustrated includes a shell 10 arranged to be connected, as by threads 11, to the end of a pusher tube of the type slidably mounted within the collet tube of an automatic screw machine. The shell 10 is provided with longitudinal splits 12 extending inwardly from the front end of the pusher shell and terminating in drilled holes 13. Two splits 12 are shown in the drawings, but it will be understood that any desired number may be used. Ordinarily on smaller sizes two splits are employed and on larger sizes three or four splits. Near its forward end the shell 10 is formed internally with a tapered groove 14 extending from the shoulder 15 to the shoulder 16 and increasing in diameter toward the shoulder 16. The shell 10 is closed in after splitting and spring tempered so that the portions of the shell separated by the splits constitute spring tongues having an inward set.

Work engaging pads 17 are arranged to be received in the groove 14 of the shell 10. In the embodiment illustrated three pads 17, each slightly shorter than one third ($\frac{1}{3}$) the circumference of the shell, are used with a relatively narrow key pad 18 in accordance with the arrangement disclosed and claimed in my copending application, Serial No. 494,641, filed July 14, 1933, now Patent No. 2,433,230. The combined circumferential length of the pads 17 and 18 is such that when no stock is positioned in the pusher, the side edges of the pads are held in abutting relation by the

2

inwardly directed spring tension of the shell 10. When stock S is engaged in the pusher the edges of the pads are separated slightly as indicated at 19 in Fig. 3, and the inner surfaces 20 of the pads then define a circle substantially equal in diameter to the diameter of the stock S.

The outer surfaces 21 of each of the pads 17 and of the pad 18 are tapered at the same angle as the bottom of the groove 14 so that when the pads are in position in the groove 14 their inner surfaces 20 are disposed axially. The axial length of the pads 17 and 18 is somewhat less than the axial distance between the shoulders 15 and 16 in the shell 10. Thus the pads are free to slide axially on the taper between the shoulders 15 and 16.

To insure that the pads 17 and 18 will always slip in the groove 14 in preference to slipping on the surface of the stock, in spite of the larger area of contact between the pads and the groove 14, the inner surfaces 20 of the pads are roughened so as to increase the friction between the pads and the stock. Preferably the pads are formed with teeth 22 consisting of circumferentially extending projections having substantially radial sides 23 disposed forwardly and sloping sides 24 disposed rearwardly.

With this arrangement the teeth 22 act to grip the bar strongly when the pusher moves forwardly, or to the right as seen in Fig. 2, and grip more lightly when the parts are moved rearwardly, or to the left as seen in Fig. 2.

The radial thickness of the pads and the angle of taper of the groove 14 are proportioned with respect to the stock S so that when the pads are moved against the shoulder 15 with the stock in place, the shell 10 is spread to its original unsplitted diameter. When the pads are moved forwardly and positioned against the shoulder 16 the shell 10 is permitted to collapse a small amount, which may be on the order of about .020 of an inch per inch of diameter of the shell. The shell 10 is preferably made with a stronger spring tension when the pads are gripping the stock and positioned against the shoulder 15 than the tension ordinarily used for spring pushers. When the pads are moved against the shoulder 16 the spring tension of the shell is relaxed, preferably to such an extent that the total spring tension is then substantially less than the tension normally used on spring pushers.

In operation the shell 10 is intermittently advanced to the right, as seen in Figs. 1 and 2, when the collet of the machine is open so as to advance a new length of stock through the collet. After the collet has closed to grip the stock the pusher is retracted to the left, as seen in Figs. 1 and 2, in position to advance a new length of stock. When the pusher moves to the right the frictional engagement of the teeth 22 against the

stock exceeds the friction of the outer surfaces of the pads 17 and 18 against the bottom of the groove 14, so that the stock and pads remain stationary while the shell advances until the pads come in contact with the shoulder 15. At this point the maximum spring tension of the shell 10 is applied to the stock so that the stock is then advanced through the remainder of the stroke of the pusher without slippage. When the shell 10 is retracted the friction between the stock and 10 the pads again exceeds the friction between the pads and the groove 14, so that the pads remain stationary on the stock until they contact the shoulder 16. Thereafter the pads are caused to slide rearwardly over the surface of the stock under the minimum spring tension of the shell 10. By reason of the relaxing of the tension of the shell 10 the stock is not marred or scratched by the retracting stroke of the pusher and the wear on the inner surfaces of the pads is greatly reduced. Scratching of the stock is further avoided, in the preferred form illustrated, by the sloping sides 24 of the teeth 22 which reduce the grip between the pads and the stock on the re- 25 tract ing stroke.

As disclosed in my aforesaid copending application, Serial No. 494,641, the pads can be readily removed from the pusher shell by first forcing radially inwardly the key pad 18 and thereafter removing the pads 17, which are then loose in the shell. For replacement the pads 17 are first placed in position and the pad 18 is then forced between the adjacent side edges of two of the pads 17, spreading the entire assembly circumferentially against the tension of the shell 10. To facilitate this operation the pad 18 is preferably formed with a slightly pointed rear end 25.

In order to simplify the removal of the pads, means may be provided to prevent rotation of the pads within the shell. As shown in Fig. 4 this means may consist of a spring tongue 26 formed in the wall of the shell by cuts 27 extending circumferentially a short distance from one side of one of the splits 12. The tongue 26 is then pressed inwardly beyond the inward set of the main body of the shell 10. An edge of one of the pads 17 next to the key pad 18 is preferably beveled off slightly, as indicated at 28 in Figs. 3 and 4, so that the tongue 26 may project into the shell slightly and abut at its end one radial side of the key pad 18. The tongue 26 is formed so as to point in a direction opposite to the direction of rotation of the stock S, so that rotation of the stock is transmitted by the pad 18 and the tongue 26 to the shell 10 and the pusher tube. With this arrangement the pads are always readily accessible for removal by simply pushing the point of a screw driver or the like through the slot 12 into engagement with the key pad 18. To avoid slippage of the screw driver or other tool used to remove the key pad, without increasing the friction of the pads in the shell, a small groove 29 may be turned in the outer surface of the pads 17 and 18.

It will be apparent that the present invention is not confined to the use of a key pad 18, as the pads 17 may all be made the same size and may be removed in the conventional way by inserting a spreading tool in the slots 12 and spreading the shell 10 open.

When it is desired to use smooth surfaced gripping pads, as for example when feeding extremely soft stock, the arrangement shown in Fig. 5 may be employed. Pads 37 and 38 are as-

sembled in the groove 14 of the shell 10 in place of the pads 17 and 18. The pads 37 and 38 have tapered outer surfaces fitting the groove 14, but are sufficiently long axially to be confined between the shoulders 15 and 16. The thickness of the pads for each particular size of stock is selected to give the desired spring gripping pressure on the stock. The stock engaging faces 39 of the pads may be smooth, as illustrated.

Although the foregoing description is necessarily of a detailed character, in order that the invention may be completely set forth, it is to be understood that the specific terminology is not intended to be restrictive or confining, and that various rearrangements of parts and modifications of detail may be resorted to without departing from the scope or spirit of the invention as herein claimed.

I claim:

1. A pusher comprising a resiliently expandable shell having a conical pad-engaging surface on its inner wall, and a plurality of mutually free stock-engaging pads having conical outer walls slidably engaging the conical surface on said shell, the inner stock-gripping surfaces of said pads being formed to increase the friction thereof against said stock, and said shell being tensioned inwardly to press the edges of said pads into mutual contact circumferentially, such as to maintain the inner gripping surfaces of said pads centered in the shell with stock removed therefrom.

2. A pusher comprising a shell having slots extending into the same from its front edge forming a plurality of spring tongues, said tongues having conical pad-engaging surfaces on their inner walls, and a plurality of separate stock-engaging pads having inner stock-gripping surfaces and conical outer walls slidably engaging the conical surfaces on said spring tongues, said tongues being tensioned inwardly and pressing the edges of said pads into mutual circumferential engagement when no stock is gripped by the pads, such as to maintain the stock-gripping surfaces centered in the shell with the stock removed therefrom, said pads being separated circumferentially and pressed against the stock by said tongues when stock is gripped therein, the area of engagement of said pads on said tongues exceeding the area of engagement of said pads on said stock, the inner surfaces of said pads being formed to increase the friction thereof against said stock.

3. A pusher comprising a resiliently-expandable shell having a groove formed on the inner surface thereof with a conical bottom wall and opposed end walls, and a plurality of separate stock-engaging pads having inner stock-gripping surfaces and conical outer walls slidably engaging the conical bottom surface of said groove, said shell being tensioned inwardly and resiliently pressing the edges of said pads into mutual circumferential engagement when no stock is gripped by the pads, such as to maintain the stock-gripping surfaces centered in the shell with the stock removed therefrom, said pads being separated circumferentially and pressed against the stock by said tongues when stock is gripped therein, the axial distance between the end walls of said groove exceeding the axial length of said pads, the inner surfaces of said pads being formed with teeth to increase the friction thereof against said stock.

4. A pusher comprising a resiliently-expandable shell having a groove formed on the inner sur-

face thereof with a conical bottom wall and opposed end walls, and a plurality of separate stock-engaging pads having inner stock-gripping surfaces and conical outer walls slidably engaging the conical bottom surface of said groove, said shell being tensioned inwardly and resiliently pressing the edges of said pads into mutual circumferential engagement when no stock is gripped by the pads, such as to maintain the stock-gripping surfaces centered in the shell with the stock removed therefrom, said pads being separated circumferentially and pressed against the stock by said tongues when stock is gripped therein, the axial distance between the end walls of said groove exceeding the axial length of said pads, the inner surfaces of said pads being formed with teeth having relatively sharp edges pointed in the direction of maximum groove diameter to increase the friction thereof against said stock.

5. A pusher comprising a shell having slots extending into the same from its front edge forming a plurality of spring tongues, said tongues having tapering pad engaging surfaces on their inner walls, the larger diameter of said surfaces being arranged toward the front edge of said shell, a plurality of separate stock engaging pads having inner stock-gripping surfaces disposed within said tongues, said tongues having an inward set and resiliently pressing the edges of said pads together into mutual contact circumferentially such as to maintain the inner gripping surfaces of said pads centered in the shell when no stock is positioned within the pads, said pads having tapering outer walls slidably engaging the tapering surfaces on said spring tongues, abutments on said tongues and said pads limiting the axial sliding movement of said pads with respect to said tongues, and stock engaging surfaces on said pads arranged to be pressed into engagement with stock by said spring tongues, the friction of said pads on the stock exceeding the friction of said pads on said tongues.

6. A pusher for screw machines and the like comprising a longitudinally slotted shell, a plurality of segmental pads disposed within said shell and arranged to grip the stock, one of said pads being of less circumferential extent than others and adapted to be pressed radially inward to free the remaining pads for removal from said shell, and means for preventing rotation of said pads within said shell in the direction of rotation

10 of the stock in the machine.

7. A pusher for screw machines and the like comprising a longitudinally slotted shell, a plurality of segmental pads disposed within said shell and arranged to grip the stock, one of said pads being of less circumferential extent than others and adapted to be pressed radially inward to free the remaining pads for removal from said shell, and means for preventing rotation of said pads within said shell in the direction of rotation 15 of the stock in the machine, said means comprising a tongue projecting into said shell from an edge of a slot therein and engaging said one pad.
